HIGH CHAIR TRAY WITH REMOVABLE INVERTIBLE INSERT

Lawrence Blazey, Bay Village, David Silverstrom, Lyndhurst, and Elmer Rocker, Shaker Heights, Ohio, assignors to Century Products, Inc., Cleveland, Ohio

Filed Mar. 22, 1972, Ser. No. 237,223

Term of patent 14 years

Int. Cl. D6—06

U.S. Cl. D6—199

Fig. 1

Fig. 2

Fig. 3

FIG. 1 is a perspective view of the high chair tray with the removable invertible insert in position in the tray with one side exposed.

FIG. 2 is a perspective view of the high chair tray with the removable invertible insert in position in the tray with the opposite side exposed from that shown in FIG. 1.

FIG. 3 is an enlarged perspective view showing the insert in greater detail.

We claim:

The ornamental design for a high chair tray with removable intervertible insert, as shown.
